UNITED STATES PATENT OFFICE.

HENRY J. BLACKMORE, OF INDIANAPOLIS, INDIANA.

RAIN-INDICATOR.

1,280,137.

Specification of Letters Patent.

Patented Oct. 1, 1918.

Application filed August 7, 1917. Serial No. 184,934.

To all whom it may concern:

Be it known that I, HENRY J. BLACKMORE, a citizen of Canada and of the Province of Newfoundland, residing at Indianapolis, in the county of Marion and State of Indiana, have invented new and useful Improvements in Rain-Indicators, of which the following is a specification.

This invention relates to improvements in rain indicators. It frequently occurs that a precipitation of rain during the night will fail to awaken the occupants of the house, the windows of which have been left open for ventilation, and the entrance of rain through the windows results in serious damage to the house furnishings.

It is the purpose of the present invention to provide a signal which will immediately be actuated by rainfall to sound the alarm.

Another object is to incorporate in the device a convenient means for draining the water from the water pocket after a rainfall, and to provide a cover-plate for the device which in the closed position serves to prevent entrance of dirt and in the open position acts to increase the flow of rainwater into the receptacle of the device and to protect the mechanism from the action of wind.

It is further proposed to provide a construction and arrangement of the float and associated contact devices whereby the construction is simplified and rendered less expensive. A preferred form of the invention is illustrated in the accompanying drawings and will be clearly understood by reference to the specification below.

In the drawings:

Figure 1 is a vertical longitudinal section through the device and includes a diagrammatic representation of the electrical connections.

Fig. 2 is a top plan view.

Fig. 3 is a vertical section on the line 3—3 of Fig. 2, showing the cover-plate in the open position.

In the preferred form shown in the drawings the device is provided with a receptacle indicated by the numeral 1 for receiving the rain. In the present instance the receptacle 1 is rectangular in form and has one side extending upwardly to constitute a wind-brake 2 which may be formed with a perforation 3 providing a convenient means for suspending the receptacle. The bottom

4 of the receptacle is formed with a depression preferably constituting a tubular pocket

5 in which is loosely fitted for free vertical movement, a float 6. Attached on the top of the float 6 in any suitable manner as by screw 24, is the horizontally disposed portion 7 of the metal strip 8 extending beyond the float and twisted intermediate of the ends to form a vertically disposed terminal portion 9. Secured as by soldering to the bottom of the receptacle 1 adjacent the pocket, is an upwardly standing conducting lug or contact guide plate 10 formed with a vertical slot 11 constituting a guide way in which is loosely engaged the vertical portion 9 of the strip 8. A contact arm 12 is secured to but insulated from a convenient portion of the receptacle 1, in the present instance by screws 13 engaged in a fiber block 14. The fiber block 14 is similarly secured as by screws 15 to the receptacle. The contact arm 12 has one end extending over the horizontal portion of the strip 8 in a position to establish connection with the latter in an upward movement of the float 6. The guide 10 and the contact arm 12 are each provided with means indicated as binding posts 16 for connection with suitable conductors 17. The conductors 17 are terminally connected respectively to an audible signal indicated as a bell 18 and a battery 19. The other terminal of the battery is connected to the remaining terminal of the bell in the usual manner.

For conveniently draining the pocket 5 it is formed in the bottom with an opening 20 having screw threaded or otherwise secured 90 therein a valve or stop-cock 21.

A lid 22 is provided for normally excluding dirt from the receptacle 1. Preferably the lid 22 is hinged to the opposite edge of the receptacle from the wind brake 2 and it is provided with flanges 23 which when the lid 22 is disposed in an outward and upwardly inclined position serve to direct the flow of water into the receptacle.

It will be noted that by the employment of the contact strip 8 constructed of a single piece of metal, ease of manufacture is promoted, and due to the twisted form given the strip, the outer portion of the strip has a broad surface area assuring good connection with the contact guide 10 while the inner or horizontal portion of the strip insures connection with the contact arm 12 irrespective of the movement of the float 5.

What is claimed is:

1. In a device of the class described, a

receptacle formed in the bottom with a tubular pocket, an upstanding vertically slotted guide adjacent said pocket, a float in said pocket, a conducting strip twisted 5 intermediately of its ends to form a horizontal portion and a vertical portion on said float, said strip having the vertical portion slidably engaged in the slot of said guide, and a contact arm mounted on said receptacle with a portion disposed over the horizontal portion of said contact element.

2. In a device of the class described, a receptacle formed in the bottom with a tubular pocket, an upstanding vertically slotted 15 guide adjacent said pocket, a float in said pocket, a conducting strip twisted intermediately of its ends to form a horizontal portion and a vertical portion on said float, said strip having the vertical portion slidably engaged in the slot of said guide, a contact arm mounted on said receptacle with a portion disposed over the horizontal portion of said contact element.

Copies of this patent may be obtained for five cents each, by addressing the "Commissioner of Patents, Washington, D. C."

tion of said contact element, said receptacle formed in the bottom of the pocket with an opening, and a valve in said opening.

3. In a device of the class described, a receptacle formed in the bottom with a tubular pocket, an upstanding vertically slotted guide adjacent said pocket, a float in said pocket, a conducting strip twisted intermediately of its ends to form a horizontal portion and a vertical portion on said float, 30 said strip having the vertical portion slidably engaged in the slot of said guide, a contact arm mounted on said receptacle with a portion disposed over the horizontal portion of said contact element, said receptacle formed in the bottom of the pocket with an opening, a valve in said opening, and a cover-plate having flanged edges hinged to 40 the lips of said receptacle.

In testimony whereof I affix my signature.

HENRY J. BLACKMORE.
